J. HARSEN.

GATE LOCK FOR DRAWBRIDGES AND ROADWAYS.

APPLICATION FILED MAY 6, 1916. RENEWED AUG. 21, 1917.

1,259,859.

Patented Mar. 19, 1918.

UNITED STATES PATENT OFFICE.

JACOB HARSEN, OF NEW YORK, N. Y.

GATE-LOCK FOR DRAWBRIDGES AND ROADWAYS.

1,259,859.

Specification of Letters Patent. Patented Mar. 19, 1918.

Application filed May 6, 1916, Serial No. 95,822. Renewed August 21, 1917. Serial No. 187,485.

To all whom it may concern:

Be it known that I, JACOB HARSEN, a citizen of the United States, residing at New York city, N. Y., have invented certain new and useful Improvements in Gate-Locks for Drawbridges and Roadways, of which the following is a clear, full, and exact description.

This invention relates to locks, and particularly to means for securing in closed position the swinging gates of draw-bridges, roadways, etc.

The gates which are located upon draw-bridges and roadways to prevent the passage of vehicles at certain times as, for example, when the draw is open, are usually arranged to swing from the two sides of the bridge or roadway toward the center, and means is usually provided for locking the adjacent ends of the gates together. It sometimes happens that the gates of a draw-bridge or roadway are closed in front of a moving vehicle which cannot be stopped in time to prevent running into the gates and sometimes drivers of vehicles fail to see gates or to allow sufficient distance in which to stop, and thus come into collision therewith. With the locking means for gates heretofore provided, the usual result of a collision of this sort is that the gates are broken open and thus no protection is provided for the bridge or roadway, often with disastrous results to the vehicle which collides with the gates.

A particular object of the present invention is to provide locking means for draw-bridge gates and the like, which will effectively secure the gates in closed position, and yet which, in the event of collision, will provide for yielding movement of the gates sufficient to bring the vehicle to a stop.

Other objects and important features of the invention will appear from the following description and the claims when considered in connection with the accompanying drawings, in which—

Figure 1 is an elevation of a pair of draw-bridge or roadway gates having the invention applied thereto;

Fig. 2 is a plan view of the locking means showing one of the spring casings in section;

Fig. 3 is an elevation of the bolt guide showing the keeper in section and the bolt in locking position; and

Fig. 4 is a perspective view of the bolt guide.

The illustrated gates 2 and 4 are provided with vertical pivots 6 and 8 at the sides of the roadway or opening which they are intended to close, these pivots turning in upper and lower bearing members 10 and 12. The gates may thus swing from an open position at one side of the roadway to a closed position in which they are in alinement and in which their ends are preferably separated, as shown in Fig. 1.

The illustrated locking means is preferably located between the ends of the gates and, as shown, comprises a bolt guide 14 and a keeper 16, the bolt guide being provided with a vertically sliding bolt 18 carried by a strap or bar 20 to which a second operating bolt 22 is connected, this bolt being provided at its lower end with an offset handle 24 connected to said bolt by a crank arm 26. By lifting up on the handle 24, the bolt 18 may be withdrawn from the bolt receiving opening in the keeper 16, as shown in dotted lines in Fig. 3, and the handle may then be turned to swing the bolt 18 over a solid portion of the bolt guide in order to retain it in elevated position.

The bolt guide 14 is provided with a base 28 having a flat face which abuts the end of the gate 2, and the keeper 16 is provided with a base 30 having a flat face which abuts the end of the gate 4. Means is provided for maintaining the bases 28 and 30 normally in rigid abutting relation to the respective gates, whereby when the bolt 18 is in locking position, the gates will be maintained in rigid alinement. The illustrated means for maintaining the bases 28 and 30 in abutting relation to the gates comprises springs 32 acting upon plungers 34, each of which comprises a bolt passing through the base of the member upon which it operates and having a head 36 bearing upon the outer face of this base, a washer 38 against which one end of the spring bears, and a nut 40 for confining the washer upon the bolt.

The other end of the spring 32 bears against the inner face of the gate end, the illustrated gate end being formed from angle bars 42 having two of their respective faces in alinement and two abutting a central member 44 of the gate. The springs 34 are preferably provided with cylindrical casings 46 which may be confined in position upon the gate by 110

straps 48, the straps upon opposite sides of the central portion 44 of the gate having out-turned portions which abut said member 44 and which are connected through said member by bolts 50.

It will be noted that the plungers 34 are connected to the bases of the locking members upon opposite sides of the point of engagement of the bolt 18 with the keeper 16, 10 and that thus they serve to hold the bases normally in rigid relation to the gates. In the event of unusual pressure upon either side of the gates, the springs 32 will permit the base members 28 and 30 to rock about 15 one of the edges of their abutting faces as the gates tend to swing into separated relation, thus permitting a limited swinging movement of the gates without breaking of the lock or injury to the gates. When the 20 force which has caused the gates to be moved out of alignment ceases to act upon the gates, the springs 32 will tend to force the gates back into alignment again.

What I claim as new is:

25 1. In combination, locking means comprising a bolt guide and a keeper, relatively swinging supports for the respective members of said locking means, and means for normally maintaining said members rigid 30 with said supports, said means being constructed to permit a yielding relative movement of said locking means and said supports in certain directions.

35 2. Locking means for use with two gates swinging about vertical axes, comprising a bolt guide and a keeper, a vertical bolt positively connecting said guide and said keeper, and yielding means for connecting said guide and said keeper to the respective gates.

40 3. Locking means for use with two gates which swing about vertical axes, comprising a bolt guide and a keeper, a vertical bolt positively connecting said guide and said keeper, and means for connecting said 45 guide and said keeper to the respective gates constructed to permit rocking movement of said guide and keeper upon the gates when the locked gates are forced toward open position.

50 4. Locking means for use with two gates swinging about vertical axes, comprising a bolt guide and a keeper adapted to be located between the adjacent ends of the closed gates, a vertical bolt positively connecting said guide and said keeper, and means for 55 yieldingly connecting said guide and said keeper to the respective gates constructed to permit said parts to rock relatively to the gates when the locked gates are forced 60 toward open position.

5. Locking means for use with two gates adapted to close an opening and pivoted at the respective sides of said opening, said means comprising a bolt guide, a keeper, 65 and a bolt for positively interlocking said

guide and said keeper, and means for maintaining said guide and keeper normally in rigid relation to said gates, constructed to permit a yielding relative movement of said locking means and said gates when excessive lateral pressure is brought to bear upon said gates. 70

6. Locking means for use with two gates adapted to close an opening and pivoted at the respective sides of said opening to swing 75 into separated relation to each other, said means comprising a bolt guide and a keeper carried by the respective gates and a bolt for positively interlocking said guide and said keeper, and connections between said locking means and said gates constructed to permit a yielding relative movement of said locking means and said gates without disturbing the interlocked relation of the members of said locking means. 80

7. Locking means for use with two gates adapted to close an opening and pivoted at the respective sides of said opening to swing into endwise relation to each other, said means comprising interlocking members carried by the opposed adjacent gate ends, means for positively holding said members against separating movement, and yielding connections between said interlocked members and the gates. 85

8. Locking means for use with two gates adapted to close an opening and pivoted at the respective sides of said opening, said means comprising a bolt guide carried by one of said gates and a keeper carried by the other gate and a bolt for positively 100 interlocking said guide and said keeper, said guide and keeper being confined upon said gates with provision for yielding movement lengthwise thereof. 105

9. Locking means for use with two gates adapted to close an opening and pivoted at the respective sides of said opening, said means comprising a bolt and a keeper carried by the respective gates, and means for confining said locking means against bodily lateral movement relative to said gates, constructed to permit a yielding rocking movement of said locking means relative to said gates when the members of said locking 110 means are in locking position. 115

10. Locking means for use with two gates adapted to close an opening and pivoted at the respective sides of said opening whereby they swing about said pivots into separated relation, said means comprising a bolt guide and a keeper carried by the respective gates and a bolt for positively interlocking said guide and said keeper, and means for retaining said guide and said keeper upon their respective supports constructed and arranged to yield in directions substantially normal to the swinging movement. 120

11. Locking means for use with two gates pivoted at the respective sides of an open- 125

ing to swing into and out of endwise relation to each other, said means comprising interlocking members carried by the respective adjacent gate ends, said members and 5 said ends having flat abutting faces, and means for yieldingly confining said members upon said ends constructed to permit each of said members to rock about an edge of its abutting face.

10 12. Locking means for use with two gates adapted to close an opening and pivoted at the respective sides of said opening, said means comprising a bolt guide carried by one of said gates, a keeper carried by the 15 other gate, a bolt for positively interlocking said guide and said keeper and means for confining said guide and keeper upon the gates against lateral movement thereon constructed to permit endwise movement relative to said gates when force is applied to 20 said gates tending to swing them into separated relation.

13. Locking means for use with two gates so pivoted at the respective sides of an opening that they swing about said pivots into and out of endwise relation to each other, said locking means being adapted to be located between the adjacent ends of the 25 gates and means for yieldingly holding said locking means in abutting relation to said ends.

14. Locking means for use with two gates so pivoted at the respective sides of an opening that they swing about said pivots into and out of endwise relation to each other, said locking means being adapted to be located between the adjacent ends of said 35 gates and yieldingly connected to said gates in abutting relation thereto, the respective members of said locking means having each two yielding connections at separated points.

15. Locking means for use with two gates so pivoted at the respective sides of an opening that they swing about said pivots into and out of endwise relation to each other, said locking means being adapted to be located between the adjacent ends of said 45 gates and comprising interlocking members, the respective members having flat abutting faces adapted to abut flat faces upon the gate ends, and yielding means for holding the respective members in abutting relation to the respective gate ends.

16. Locking means for use with two gates so pivoted at the respective sides of an opening that they swing about said pivots into and out of endwise relation to each other, said locking means being adapted to be located between the gate ends, and means for connecting said locking means to the 55 respective gates constructed to prevent bodily lateral movement relative to said gates but to permit yielding movement lengthwise of said gates.

17. Locking means for use with two gates pivoted at the respective sides of an opening to swing into and out of endwise relation to each other, of means for locking said gates in closed position comprising a bolt guide and a keeper, said lock members having flat faces adapted to abut the end faces of the gates, and means located at either side of the point of engagement of the bolt with its keeper for yieldingly holding said guide and said keeper in abutting relation 70 to the respective associated gate ends.

18. The combination with roadway gates pivoted to swing in and out of endwise relation, of locking means for the adjacent ends of said gates, comprising interlocking members provided with means to maintain a positive but yielding connection between said gate ends against horizontal pressures, said interlocking members having a relatively vertical movement for being locked together 80 or unlocked.

19. The combination with roadway gates pivoted to swing in and out of endwise relation, of locking means for the adjacent ends of said gates, comprising interlocking members arranged to maintain a positive connection between said gate ends when subjected to horizontal pressures, a spring support for at least one of said interlocking members to permit the same to yield while 90 maintaining said connection, said interlocking members having a relatively vertical movement for being locked together or unlocked.

Signed at New York, N. Y. this 4th day 95 of May 1916.

JACOB HARSEN.
